UNITED STATES PATENT OFFICE.

ROBERT C. GROH, OF ST. PAUL, MINNESOTA, ASSIGNEE, BY DIRECT AND MESNE ASSIGNMENTS, OF THREE-EIGHTHS TO THOMAS P. MCKAY, THREE-EIGHTHS TO PAUL GOTTFRIED, AND ONE-FOURTH TO OLE C. RINDAL, ALL OF ST. PAUL, MINNESOTA.

AUTOMOBILE-ALARM.

1,151,264.

Specification of Letters Patent. Patented Aug. 24, 1915.

Application filed October 3, 1912. Serial No. 723,737.

To all whom it may concern:

Be it known that I, ROBERT C. GROH, a citizen of the United States, residing at St. Paul, in the county of Ramsey and State of Minnesota, have invented certain new and useful Improvements in Automobile-Alarms, of which the following is a specification.

My invention relates to improvements in thief alarms for automobiles, its object being particularly to provide an improved form of thief alarm actuated by the battery or magneto current of an automobile to ring an alarm when the current is turned on.

To this end the invention consists in the features of construction, combination, and arrangement of parts hereinafter described and claimed.

In the accompanying drawings forming part of this specification, Figure 1 is a side view, broken away, of an automobile showing my alarm box fastened upon the dashboard, with the door of the box open; Fig. 2 is a diagrammatic view of the wiring of an automobile illustrating one method of inserting my invention therein; Fig. 3 is a similar view of the wiring illustrating a modified method of inserting my invention therein; Fig. 4 is a vertical transverse section through the alarm box; Fig. 5 is a section on line α — α of Fig. 4; and Fig. 6 is a detail view of a portion of the alarm box showing a modified construction of switch.

Referring to the drawings, A represents an automobile, B the engine cylinders, C the batteries, D the magneto, E the induction coil box, and F the ordinary switch for turning on the battery or magneto current.

Adapted to be fastened upon the dashboard, as shown in Fig. 1, is the alarm containing box G. Mounted within the box is a bell 2 in connection with which is arranged a hammer 3 supported by an armature 4 having pivotal support 5, and adapted to be actuated in the ordinary manner by electromagnets 6 against the tension of the armature controlling spring 7. Conducting wires 8 and 9 lead into the box through an opening 10, the wire 8 leading directly to the armature frame and the wire 9 leading to a contact 11 forming part of the alarm switch. The contact 11 is supported upon a plate 12 which also supports an independent contact 13 connected by a conducting wire 14 with the electromagnet frame. The contacts 11

and 13 are adapted to be electrically connected by a slideable bolt 15 forming part of the lock 16 and adapted to be thrown into position connecting said contacts 11 and 13 by the key actuation of said lock.

In the arrangement illustrated in Fig. 2 I show the wire 8 leading from the primary wire 17 and the wire 9 of the alarm leading to the ground or return wire 18 of the wiring system of the car. In the arrangement shown in Fig. 2 it will be evident that when the bolt 15 is actuated to connect the contacts 11 and 13 and with the battery or magneto current turned on, the current will pass through the electromagnet 6 and actuate the bell to sound an alarm.

In Figs. 3 and 6 is shown an arrangement of wiring in which the magneto or battery current when turned on will pass through a portion of the alarm mechanism without sounding an alarm unless the alarm control 75 is switched into circuit. As shown in this arrangement the alarm apparatus is tapped into the wire 19 leading from the coil box to the spark plug. With this arrangement I utilize the modified form of alarm control- 80 switch shown in Fig. 6. Referring to Fig. 6, 20 and 21 represent two opposed contacts, the contact 20 being connected with the alarm apparatus by a conducting wire 22 corresponding with the wire 14 shown in Fig. 4. Arranged below the contacts 20 and 21 are similar contacts 23 and 24. The contact 23 is connected by an outlet wire 25 with the secondary circuit wire 19 and also connected with the alarm apparatus through 90 the wire 26. The contacts 21 and 24 are electrically connected by a connection 27, an inlet wire 28 leading from the secondary current wire 19 to the contact 24. The switch bar 29 corresponds with the bolt 15. 95 In the construction shown in Fig. 4 and normally stands electrically connecting the contacts 23 and 24. When it is desired to actuate an alarm the switch bar will be moved into position connecting the contacts 20 and 21. With the switch bar in the position shown in Fig. 6 the secondary current passing through the wire 19 will pass through the wire 28, the contacts 24 and 23, the switch bar 29, and out through the wire 25. 100 When the switch bar is moved into co- 105 operation with the contacts 20 and 21 the current will pass through the wire 28, the contacts

24 and 21, the switch bar 29, and through the contacts 20, wire 22 to the alarm apparatus, passing back to the contact 23 through the wire 26 and out through the wire 25 5 completing the circuit.

I claim as my invention:

In combination with the electric wiring of an automobile, an alarm bell, coöperating electromagnets, electric wiring for said magnets, separated electric contacts interposed 10 between said alarm wiring and main wiring, a key actuated plunger operable to close said

contacts for the purpose set forth, said plunger being in circuit with the electric wiring of the automobile when in circuit with the 15 alarm apparatus, and also when out of circuit with the alarm apparatus.

In testimony whereof I affix my signature in presence of two witnesses.

ROBERT C. GROH.
